US0D1076249S

(12) **United States Design Patent** (10) **Patent No.:** **US D1,076,249 S**
(45) **Date of Patent:** **** May 20, 2025**

(54) **PET FEEDER**

(71) Applicant: **SHENZHEN CHENBEI TECHNOLOGY CO., LTD.**, Shenzhen (CN)

(72) Inventor: **Alex William Chow**, Shenzhen (CN)

(73) Assignee: **SHENZHEN CHENBEI TECHNOLOGY CO., LTD.**, Shenzhen (CN)

(**) Term: **15 Years**

(21) Appl. No.: **29/927,166**

(22) Filed: **Feb. 2, 2024**

(51) **LOC (15) Cl.** **30-07**

(52) **U.S. Cl.**

USPC **D30/122**

(58) **Field of Classification Search**

(57) **CLAIM**

The ornamental design of a pet feeder as shown and described.

DESCRIPTION

FIG. 1 is a top-left perspective view of an embodiment of the pet feeder showing my new design;
FIG. 2 is a front view thereof;
FIG. 3 is a rear view thereof;
FIG. 4 is a left view thereof;
FIG. 5 is a right view thereof;
FIG. 6 is a top view thereof; and,
FIG. 7 is a bottom view thereof.

(Continued)

The broken lines in the figures are included for the purpose of illustrating portions of the Pet Feeder and do not form any part of the claimed design.

1 Claim, 5 Drawing Sheets
